COUPLER

Edmund P. Kinne and Frank H. Kayler, Alliance, Ohio, assignors to American Steel Foundries, Chicago, Ill., a corporation of New Jersey

Application June 10, 1937, Serial No. 147,454

14 Claims. (Cl. 213—166)

Our invention pertains to coupler mechanisms for railway cars and more particularly to a design of coupler parts and associated operating means which will facilitate the operation of the 5 coupler mechanism from the side of the car.

Generally considered, an object of our invention is to improve the operation of the automatic coupler and more particularly the general design of bottom operated coupler shown in Janney Patent No. 1,443,821.

Another object of our invention is to modify the said coupler design and associate therewith novel parts which will permit bottom operation of this type of coupler by rotary means.

15 A still further object contemplated by our invention is so to associate an operating rod with the said coupler as to produce maximum efficiency and simplicity of design and at the same time insure a maximum safety on the part of operatives.

20 Yet another object of our invention is to design such a rotary bottom operated mechanism having a novel and highly efficient form of anti-creep, thus greatly increasing the positive action of the 25 coupler in operation.

With these and various other objects in view, our invention may consist of certain novel features of construction and operation as will be 30 more fully described and particularly pointed out in the specification, drawings and claims appended hereto.

In the drawings which illustrate an embodiment of the device and wherein like reference characters are used to designate like parts—

35 Figure 1 is an end elevation of a railway car embodying the features of our invention;

Figure 2 is a fragmentary top plan view of the structure shown in Figure 1;

40 Figure 3 is a fragmentary side elevation of the structure shown in Figures 1 and 2;

Figure 4 is a vertical sectional view of a coupler embodying our invention, the parts being shown in locked position;

45 Figure 5 is a vertical sectional view similar to that shown in Figure 4 except that the parts are in lock-set position;

Figure 6 is a vertical sectional view similar to that shown in Figures 4 and 5 with the parts in full knuckle throw position;

50 Figure 7 is a fragmentary view corresponding in general to that shown in Figures 4 and 5 and disclosing the relative positions assumed by the rotor and the lifter at a point intermediate the positions shown in Figures 4 and 5 as the anti-creep mechanism is released;

Figure 8 is a fragmentary front view of the coupler shown in Figures 4, 5 and 6, illustrating more particularly the lug and trunnion structure at the bottom of the coupler head;

Figure 9 is a sectional view through the structure shown in Figure 8, the section being taken substantially in the plane indicated by the line 9—9 of Figure 8;

Figure 10 is a side elevation of the rotor;

Figure 11 is a front elevation of the rotor;

Figure 12 is a top plan view of the rotor; and

Figure 13 is a front elevation of the lifter, side elevations of which are clearly shown in Figures 4, 5 and 6.

Referring to the drawings in more detail, it 15 may be noted that the coupler includes the usual coupler head 2 of the form previously described in the above mentioned Janney Patent No. 1,443,821 and having a pivotally mounted knuckle 4 and a guard arm portion 6 (Figure 2), the 20 knuckle 4 being secured to the coupler head 2 by means of the pivot pin 8. In the above mentioned patent both a bottom operating type and a top operating type of this form of coupler are described. The present invention comprehends a 25 modification of the bottom operating type only.

Referring more particularly to Figures 4 to 9, it may be observed that the coupler head 2 has the depending lugs 10—10 (Figure 8) joined by the integral trunnion 12, said lug and trunnion structure being formed immediately to the rear of the bottom opening in the coupler head (Figures 4 to 6). The rotor 14 (Figures 10, 11 and 12) is of a novel form, having the hook-like projection 16 at one end for cooperation with the trunnion 12 and having at its opposite end the opening 17 (Figure 11) within which may be received the lower end of the lifter 20, the eyes 18 in the opposite sides of the rotor being aligned with the elongated slot 22 in the bottom of the lifter, the parts being retained in assembly by the pin 24 and the cotter 26. The bridge portion 19 (Figures 11 and 12) integrally joins the side portions within which are formed the eyes 18. The pin 24 serves as a trunnion means, permitting pivotal action and limited sliding movement between the rotor 14 and the lifter 20 through its cooperation with the elongated slot 22. The upper end of the lifter 20 has the jaw 28 within which may be received the bar 30 formed as an integral part of the lock 32 as described in the aforesaid Janney patent. The rotor 14 has the shoulder 34 which serves as an abutment for the hooked end 36 of the operating rod 38 (Figures 1 and 2) after the said end has been inserted through the eye 56

39 (Figure 12) centrally formed in the rotor 14, whereby rotation of the operating rod in a counter-clockwise direction as viewed in Figure 3 will cause the rotor 14 to turn also in a counter-clockwise direction (Figures 4 to 7) about the trunnion 12 by engagement therewith of its hook-like end 16. The relation of the various parts in the locked position is shown in Figure 4 and in lock-set position in Figure 5. In the lock-set position 5 of Figure 5 it will be noted that the lower end 40 of the lock is seated upon the shelf 42 integrally formed on the coupler head and the rotor 14 is in an elevated position. Figure 6 shows the maximum position of counter-clockwise rotation of 10 the rotor 14, the operating rod 38 having been rotated to the maximum from its rest position 15 as shown in Figures 3 and 4.

With the parts in lock-set position or full knuckle throw position as shown respectively in 20 Figures 5 and 6, it will be apparent that the weight of one end of the operating rod as well as the weight of the lifter 20 and rotor 14 are eccentrically positioned with respect to the support point which constitutes the trunnion 12, 25 thus tending to rotate the parts back to the normal locked position shown in Figure 4.

Figures 1 to 3 show the application of this novel form of coupler and operating rod arrangement as applied to the end of a railway car. It will be 30 observed that the coupler head 2 is supported on the longitudinal axis of the car body 44 and that the angle bracket 46 is secured on the end of the car body adjacent the outer corner as supporting means for the operating rod 38. The 35 said bracket 46 has the jaw opening 48 within which may be received one end of the substantially horizontal portion of the operating rod 38, securing means for the rod within the jaw being provided in the form of the rivet 50. It will be observed that the handle 52 of the operating 40 rod 38 is in abutment against the bracket 46 as at 54 when the parts are in locked position as shown in Figures 3 and 4. It may be further observed that counter-clockwise rotation of the 45 operating rod handle 52 as viewed in Figure 3 for operation of the rotor and other parts of the coupler as previously described results in a movement which elevates the inner end 36 of the operating rod 38 along with the rotor 14 which turns about the trunnion 12. It may also be observed as shown in Figure 2 that the inner end 50 of the operating rod extends outwardly from the car body and is in an offset position with relation to the jaws 48 constituting its point of support at the outer end. It will be apparent, therefore, that the weight of the inner end of the 55 operating rod 38, as well as the weight of the rotor 14 and the lifter 20, acts to return the operating rod to its normal position as shown in Figure 3 when the parts are released from the lock-set position or the knuckle throw position as shown in Figures 5 and 6 respectively. Moreover, the weight of the inner end of the operating rod is added to the weight of the lifter and the rotor to retain the parts in their lowermost or locked position as shown in Figure 4 and thus to prevent their accidental release from the said locked position.

The operation of the safety anti-creep which 70 we have embodied in this improved coupler design is shown by a comparison of Figures 4 and 7. In Figure 4 the parts are shown in locked position with the anti-creep operative. In this position the shoulder 56 provides stop means 75 against which the bridge 19 will abut and pre-

vent accidental turning of the rotor such as might otherwise be caused by a jolting action in operation. With the parts at rest as shown in this position the pin 24 is seated against the lower end of the elongated slot 22 and accidental turning movement of the rotor is prevented by the 5 said engagement of the bridge 19 on the rotor against the shoulder 56 on the lifter. If, however, the handle 52 of the operating rod 38 is seized and rotated, the parts will be moved to 10 the position shown in Figure 7 wherein the pin 24 is positioned in the opposite end of the slot 22, the relative position of the rotor with respect to the bottom of the lifter having been sufficiently shifted to permit the bridge 19 to clear the shoulder 15 56, thus permitting free rotary movement between the parts as the handle of the operating rod is further rotated.

It is to be understood that we do not wish to be limited by the exact embodiments of the device 20 shown, which are merely by way of illustration and not limitation, as various and other forms of the device will of course be apparent to those skilled in the art without departing from the spirit of our invention or the scope of the claims. 25

We claim:

1. In a coupler mechanism the combination of 30 a coupler head, a depending lug integrally formed therewith, a lock operable therein, a lifter having a connection to said lock, a rotor pivotally connected at one end to said lifter, pivotally supported at its opposite end on said lug and having an eye and a shoulder intermediate said ends, cooperating anti-creep means formed on said lifter and said rotor and operative independently 35 of other parts, and an operating rod having a knuckled end received in said eye and engageable with said shoulder, the opposite end of said operating rod being supported from an associated car body, said operating rod being free of support 40 between its connection to said car body and its connection to said rotor.

2. In a coupler mechanism the combination of 45 a coupler head, an integral lug having a trunnion portion, a lock operable in said head, a lifter connected to said lock at one end and at its opposite end pivotally connected to a rotor, said rotor having its other end pivotally connected to said trunnion and having an eye and a shoulder intermediate its ends, means on said rotor cooperating 50 with means on said lifter to prevent accidental creeping of said parts, said cooperating means being operative independently of other parts, and an operating rod having a knuckled end received in said eye and engageable with said shoulder for operation of said coupler, said operating rod having its outer end connected to an associated car body and being free of connection intermediate its ends, whereby the inner end of 55 said operating rod is eccentrically positioned with respect to its support on said car body.

3. In a coupler mechanism the combination 60 of a coupler head, an integral lug having a trunnion portion, a lock operable in said head, a lifter connected to said lock at one end and its opposite 65 end pivotally connected to a rotor, said rotor having its other end pivotally connected to said trunnion and having an eye and a shoulder intermediate its ends, co-operating anti-creep means on 70 said lifter and said rotor operative independently of other parts, and an operating rod having a knuckled end received in said eye and engageable with said shoulder for operation of said coupler, said operating rod having its outer end connected to an associated car body and being free of con- 75

nection intermediate its ends, whereby the inner end of said operating rod is eccentrically positioned with respect to its support on said car body, said eccentric positioning of the inner end 5 of said operating rod acting to retain said rotor in its lowermost or locked position.

4. In a coupler mechanism the combination of a coupler head, a lock operable therein, a lifter connected at the upper end of said lock and having 10 its lower end pivotally and slidably connected to one end of a rotor, said pivotal and slidable connection comprising a pin secured to said rotor receivable in a slot on said lifter, cooperating anti-creep means on said lifter and rotor and 15 operative when said pin is in the bottom of said slot, the opposite end of said rotor having a pivotal connection with the bottom of said coupler head, an eye intermediate the ends of said rotor, and an operating rod having a knuckled end received 20 in said eye, said operating rod rotating about its longitudinal axis for operation of said coupler.

5. In a coupler mechanism the combination of a coupler head having a trunnion integrally 25 formed thereon, a lock operable in said head, a lifter engaging said lock, a rotor having pivotal connections at its respective ends with said trunnion and said lifter, said pivotal connection between said rotor and said lifter comprising a slot 30 on said lifter receiving a pin secured to said rotor, cooperating anti-creep means on said lifter and rotor operative when said pin is in the bottom of said slot, an eye intermediate the ends of said rotor, and an operating rod having a knuckled 35 end received in said eye and its opposite end connected to a car body, said operating rod being free of support intermediate its ends.

6. In a coupler mechanism the combination of a coupler head, an integral lug having a trunnion 40 portion, a lock operable in said head, a lifter having its upper end connected to the top of said lock and having its opposite end pivotally and slidably connected to a rotor, cooperating anti-creep means on said lifter and rotor effective independently of other parts, said rotor having its 45 other end pivotally connected to said trunnion and having an eye and a shoulder intermediate its ends, and an operating rod having a knuckled end received in said eye and engageable with said shoulder for operation of said coupler.

7. In a coupler mechanism the combination of a coupler head, an integral lug having a trunnion portion, a lock operable in said head, a lifter connected to the top of said lock, a rotor pivotally 55 connected at one end to said trunnion and at its opposite end to the lower end of said lifter, the connection between said rotor and said lifter being also slidable and including a slot on said lifter receiving a pin secured to said rotor, cooperating 60 anti-creep means on said lifter and rotor operative when said pin is in the bottom of said slot, an eye formed intermediate the ends of said rotor, and an operating rod having a knuckled end connected to said eye for operation of said 65 coupler.

8. In a coupler mechanism the combination of a coupler head having a trunnion integrally formed at the bottom thereof, a lock operable in said head, a lifter connected to the top of said lock, a rotor having one end connected to said 70 trunnion and its opposite end pivotally and slidably connected to said lifter, said slidable connection comprising a slot on said lifter receiving

a pin secured to said rotor, cooperating anti-creep means on said lifter and said rotor, said anti-creep means being effected independently of other parts when said pin is at the bottom of said slot, and means for operating said rotor. 5

9. In a coupler mechanism the combination of a coupler head having a trunnion integrally formed thereon, a lock operable in said head, a lifter engaging said lock, a rotor having pivotal connections at its respective ends with said trunnion and said lifter, the connection between said rotor and said lifter being also slidable and including an elongated slot in said lifter receiving a pin secured to said rotor, cooperating anti-creep means on said lifter and said rotor effective when said pin is at the bottom of said slot, an eye intermediate the ends of said rotor, and an operating rod having a knuckled end received in said eye and its opposite end connected to a car body. 10 15

10. In a coupler mechanism the combination of a coupler head having a trunnion thereon, a lock operable in said head, a lock lifter, a rotor having a pivotal connection at one end of said trunnion and at its opposite end to said lifter, and anti-creep means on said rotor cooperating with means on said lifter, said anti-creep means on said rotor and lifter being operative independently of other parts of said coupler, said rotor being movable about said trunnion for operation 20 25 30 of said lifter to said lock.

11. In a coupler mechanism the combination of a coupler head comprising a lock and lock operating means including a lifter, a rotor and means on said lifter cooperating with means on said rotor to provide an anti-creep for said lock, said anti-creep means on said rotor and lifter being operative independently of other parts. 35

12. In a car coupler a coupler head comprising lock operating means including a lifter and a rotor, said lifter and rotor having a sliding pivotal connection comprising a slot on said lifter receiving a pin secured to said rotor, and cooperating anti-creep means on said lifter and rotor operative when said pin is at the bottom of said 40 45 slot.

13. A car coupler comprising a lock, a lifter connected to the top of said lock, a rotor, and operating means for said rotor, said lifter having means cooperating with means on said rotor 50 to provide an anti-creep, whereby said rotor is prevented from accidental rotation while permitted rotation under actuation of said operating means, said cooperating means including an elongated slot on said lifter receiving a pin secured 55 to said rotor, said anti-creep being effective when said pin is at the bottom of said slot.

14. In a car coupler, a lock, a lifter, and a rotor, operating means for said rotor, a pivotal and slidable and anti-creep connection between said lifter and said rotor in the form of spaced walls at one end of said rotor, a bridge joining said walls at their outer extremity, a pin connecting said walls at intermediate points, the lower end of said lifter extending between said walls and 60 having an elongated slot receiving said pin, and a shoulder on said lifter end cooperable with said bridge when said pin is at the lower end of said slot and released from engagement therewith when said pin is at the upper end of said slot. 65 70
